[57] CLAIM

The ornamental design for a glove bottle, as described and shown.

DESCRIPTION

FIG. 1 is a side view of the glove bottle, showing in phantom lines a person's forearm; the phantom line disclosure not being a part of the design, but for environmental purposes to illustrate that a person's hand will fit inside the glove; FIG. 2 is a top view of the glove bottle; FIG. 3 is a front view of the glove bottle; FIG. 4 is a side view of the glove bottle, looking at the side not shown in FIG. 1; and, FIG. 5 is a perspective view looking at the rear of the glove bottle and at the side of the glove bottle shown in FIG. 4.
